UNITED STATES PATENT OFFICE.

HENRY DOYLE, OF NEW YORK, N. Y.

DESIGN FOR A CALENDAR.

SPECIFICATION forming part of Design No. 34,604, dated June 4, 1901.

Application filed April 30, 1901. Serial No. 58,222. Term of patent 3½ years.

To all whom it may concern:

Be it known that I, HENRY DOYLE, a citizen of the United States, residing at New York, borough of Manhattan, and State of New York, have invented and produced a certain new and original Design for Calendars, of which the following is a specification, reference being had to the accompanying drawings, forming part thereof, and in which—

Figure 1 is a front elevation of a calendar, showing my new design; and Fig. 2 is an edge view of the same.

The leading or material features of my design are a rectangular field, in which are arranged a rectangular object, a representation of a golf-player, and on each side of the latter ornaments representing a golf-club and a golf-ball.

Referring to the drawings, A indicates and represents a rectangular field, which is surrounded by a border *a*, representing Scotch

plaid. At the upper end of the field is an ornamentation *b*, representing a staff of music, and at one of the lower corners of the same is a rectangular calendar or ornament *c*, and between the same and the music-staff is a representation *d* of a golf-player, on each side of which are respectively arranged ornamental objects *e f*, representing a golf-club and a golf-ball.

g represents a shoestring.

What I claim as new is—

The design for a calendar, as herein shown and described.

In testimony that I claim the foregoing as my invention I have signed my name in presence of two subscribing witnesses.

HENRY DOYLE.

Witnesses:

PAUL GOEPEL,
GEORGE GEIBEL.
